(57) **CLAIM**

The ornamental design for a display screen with transitional icon, as shown and described.

DESCRIPTION

FIG. 1 is a first image in a sequence of a display screen with a transitional icon, showing the new design;

FIG. 2 is a second image thereof;

FIG. 3 is a third image thereof; and,

FIG. 4 is a fourth image thereof.

The appearance of the transitional icon sequentially transitions between the images shown in FIGS. 1-4.

The process or period in which one image transitions to another image forms no part of the claimed design.

The broken lines showing the display screen form no part of the claimed design.

The shaded areas of the drawings illustrate a contrast in appearance. The varying shades of the shaded areas of the drawings could be displayed as varying shades illustrating a contrast in appearance.
